UNCURLING DEVICE AND GAUGE FOR
SEWING MACHINESWilliam H. Pfeiffer, Philadelphia, Pa., assignor to
Union Special Machine Company, Chicago, Ill.,
a corporation of Illinois

Application January 16, 1934, Serial No. 706,884

2 Claims. (Cl. 112—20)

The invention relates to new and useful improvements in a fabric guiding and uncurling device for directing fabric sections to a stitching mechanism, and more particularly to an uncurling device used in connection with a sewing machine wherein the fabric sections to be stitched are supported by feed wheels rotating about vertical axes.

In the uncurling device now in use, the fabric sections as they pass through the guiding and uncurling devices are gripped more or less lightly between the center plate and the yieldingly mounted uncurling members associated therewith. The operator supports and feeds the fabric sections to the uncurling device, and by raising and lowering the same, regulates to a certain extent the height of the fabric sections as they leave the uncurling or guiding device. Fixedly mounted guide pins carried by the center plate and extending through openings in the guiding and uncurling devices have been used for limiting the upward movement of the fabric sections. These pins serve as a gauging means for determining the height of the fabric sections as they leave the uncurling devices, so that they will be properly directed to the feed wheels.

An object of the present invention is to provide a gauging means which is located wholly in rear of the fabric guiding and uncurling devices and which may be adjusted to different set positions so that the extent to which the fabric sections project above the feed wheels may be varied, if desired.

A further object of the invention is to provide a device, of the character referred to, wherein the gauging means is located as close as possible to the stitching point and to the point of engagement of the fabric sections by the feed wheels so that the fabric sections can be fed to the stitching mechanism before they tend to curl up again.

In the drawing—

Figure 1 is a side view of a combined uncurling device and gauge embodying the improvements;

Fig. 2 is a similar view with the fabric guiding and uncurling device broken away at one side so as to show the shaping of the center plate;

Fig. 3 is a rear view of the structure shown in Fig. 1;

Fig. 4 is a view partly in plan and partly in section taken from a point above the fabric sections, and showing the relation of the gauging member to the feed wheels and stitching mechanism of the sewing machine.

The invention is directed to a combined uncurling and gauging device for directing fabric

sections to the stitching mechanism whereby the edges of the fabric sections are joined and covered by over edging stitches. The fabric sections are supported by feed wheels or feed cups which are illustrated diagrammatically in Fig. 5 of the drawing at 1 and 2. The needle is indicated at 3 and the looper which cooperates therewith is indicated at 4. The stitch finger over which the stitches are formed is indicated at 5. This type of machine is very common, and further description thereof is not thought necessary. The fabric sections which are indicated at F and F' are supported by the feed wheels so that the edge portions thereof project above the feed wheels and the needle passes through said edge 15 portions adjacent the edges thereof. The looper engages the needle thread loop and then moves to a position at the other side of the fabric sections where its loop is presented for the needle to enter.

This type of machine is particularly adapted for stitching knitted fabrics wherein the edge portions when they are cut for the shaping of the garment that is to be produced will curl. It is essential to provide a device for uncurling and directing the fabric sections. This combined uncurling and guiding device consists of a center plate 6 which is relatively thin and lies between the two fabric sections. The fabric sections are placed by the operator in a vertical position with 30 this center plate between the two fabric sections. The uncurling devices are indicated at 7 and 8 in the drawing. The uncurling device 7 is mounted on a pivot pin 9 carried by projecting lugs 10, 10 which are formed as a part of a support 11. The 35 center plate 6 is attached to this support 11, or may be made an integral part thereof. It is essential, however, that this center plate shall be relatively thin so that the fabric sections will be close to each other as they pass through this uncurling and guiding device. The uncurling device is provided with a curved upper face 12 which leads to a second curved face 13. This curved face serves as a means for unrolling the curled edge of the fabric section. The uncurling and 45 guiding device 8 is carried by a pivot pin 14 mounted in the lugs 15 projecting from the opposite side of the support 11. This guiding and uncurling device is shaped similar to the guiding and uncurling device 7. A compression spring 16 50 secured to the upper ends of the uncurling devices 1, 8 and passing through an opening 17 in the center support 11 normally turns said uncurling devices so as to cause the same to yieldingly clamp the fabric sections against the center plate. 55

Fig. 1 is a side view of a combined uncurling device and gauge embodying the improvements; Fig. 2 is a similar view with the fabric guiding and uncurling device broken away at one side so as to show the shaping of the center plate; Fig. 3 is a rear view of the structure shown in Fig. 1; Fig. 4 is a view partly in plan and partly in section taken from a point above the fabric sections, and showing the relation of the gauging member to the feed wheels and stitching mechanism of the sewing machine.

The center plate 6 is cut away at the rear face thereof as indicated at 18. Located in this cut-away portion is a gauge member 19. Said gauge member 19 is in the form of a plate, and this plate is disposed in a plane at right angles to the path of travel of the fabric sections through the uncurling device. The lower edge of this plate is the guiding or gauging edge of the plate. The plate is attached to the support 11 by a screw 20 which passes through a slot in the plate and is threaded into said support. This provides a means whereby the plate may be adjusted vertically to different set positions. It is noted that the plate is bent so as to lie immediately in rear of the center plate and the uncurling devices so that it contacts with the edges of the fabric sections for gauging the position thereof while the edges of the fabric sections are under control and supported by said uncurling devices.

20 The fabric sections are placed by the operator against the center plate and beneath the uncurling devices. These uncurling devices grip the fabric sections lightly, but support the fabric sections, due to the fact that the edges which are being uncured overlie the curved edge portions 12 of said uncurling devices. The operator also supports the fabric sections and directs said sections to the uncurling and guiding device. The purpose of the gauge member 19 is to regulate the height of the fabric sections as they leave the uncurling device. It is essential that these fabric sections shall be maintained at the vertical height which is desired for the most efficient covering of the edges of the fabric sections by the stitching mechanism. The uncurling device does not positively hold the fabric sections raised. This is accomplished by the operator in the feeding of the fabric sections to said uncurling and guiding device. When the gauge for determining the height 40 of the fabric sections is placed all the way to the rear of the uncurling device, the operator has a greater range of movement wherein the fabric sections may be lifted and then lowered in order to bring them to the proper level. Furthermore, 45 by placing this gauging member all the way to the rear of the uncurling devices, it is brought nearer to the stitch finger and the needle. After the fabric sections leave the gauging member,

there are no parts of the uncurling device which contact therewith to disturb the movement of the edges in a direct line beneath the stitch finger to the needle. By mounting this gauge member so that it can be vertically adjusted to different 5 set positions, the height of the fabric sections relative to the feed wheels may be varied, and thus the extent to which the fabric sections project above the feed wheels varied. This enables the operator to obtain just the desired depth of stitch 10 through the edge portions or the distance between where the needle punctures the fabric sections and the edges thereof.

It is obvious that changes in the shaping of the gauging member and the manner of mounting the same may be made without departing from the spirit of the invention as set forth in the appended claims.

Having thus described the invention, what I claim as new and desire to secure by Letters Pat- 20 ent, is—

1. In a sewing machine, a combined guide and gauge for uncurling and directing fabric sections including a vertically disposed center plate, yieldingly mounted uncurling and guiding devices disposed at opposite sides of said center plate, and a gauge member disposed immediately in rear of said center plate and said uncurling and guiding devices for contacting with the edges of the fabric sections while said fabric sections are under 30 the control of the uncurling and guiding devices for gauging the position of the fabric sections.

2. In a sewing machine, a combined guide and gauge for uncurling and directing fabric sections including a vertically disposed center plate, yieldingly mounted uncurling and guiding devices disposed at opposite sides of said center plate, a gauge member disposed immediately in rear of said center plate and said uncurling and guiding devices for contacting with the edges of the fabric sections while said fabric sections are under 35 the control of the uncurling and guiding devices for gauging the position of the fabric sections, and means for supporting said gauge member whereby it may be adjusted vertically to different 40 set positions relative to the devices for uncurling and guiding the fabric sections.
